UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

ROTARY-HOOK SEWING-MACHINE.

1,269,686.

Specification of Letters Patent. Patented June 18, 1918.

Application filed June 3, 1914, Serial No. 842,594. Renewed July 28, 1915. Serial No. 42,456.

To all whom it may concern:

Be it known that I, ALBERT H. DE VOE, a citizen of the United States, residing at Westfield, in the county of Union and State 5 of New Jersey, have invented certain new and useful Improvements in Rotary-Hook Sewing-Machines, of which the following is a specification, reference being had therein to the accompanying drawings.

10 This invention relates to an improvement in that class of loop-takers comprising a circularly moving loop-seizing member provided with a beak within the circular path of movement of which a thread-case containing a mass of lower thread is suspended; and it has for its primary object to provide 15 advantageous means for sustaining the thread-case wholly independently of the loop-seizing member so as to obviate friction and prevent the jamming of the thread 20 between such moving parts while obviating the application thereto of lubricating means likely to soil the stitching threads in the loop-casting operation. It has for a further 25 object the reduction of weight of the moving parts by restricting the function of the loop-taking member to its normal loop-seizing and casting operation without affording the usual support for the thread-case and its 30 contained mass of lower thread. It has for another of its objects to provide a normally stationary support for the thread-case between which and the latter the needle-thread loop may be readily drawn up to the 35 work without excessive strain thereon.

In the preferred form of the improvement, the loop-seizing member comprises a disk having a segmental projection extending throughout only a small portion of the 40 circumference and provided with a loop-taking beak moving in a circular path within which is disposed the floating thread-case provided in its upper side with a channel having overhanging lips and sustained by 45 a hanger having a member entering and loosely embraced by said channel and affording a support upon which said lips rest. The hanger is provided at one side of its supporting tongue with a stop-finger and a 50 yielding latch-arm whose operative portions are spaced apart to embrace one side of the thread-case, the yielding member being retractable for removal of the thread-case from and endwise of the supporting tongue.

The hanger is preferably mounted upon a 55 support adapted to swing outwardly to withdraw the thread-case from the loop-seizing member for access to the contained bobbin and for purposes of threading, locking means being provided to maintain the 60 support in operative position.

The loop-seizing member is preferably mounted upon a rotary loop-taker shaft journaled in a laterally adjustable frame which is mounted concentrically with the 65 actuating shaft to which the loop-taker shaft is operatively connected by means of a pair of bevel-gears. By this means the loop-taker may be laterally adjusted relatively to a single needle, or a plurality of loop-takers 70 may be similarly adjusted to coöperate with a corresponding number of needles set at different gages apart.

In the accompanying drawings, Figure 1 is a side elevation, partly in section, representing a well-known form of feed-up-the-arm twin-needle sewing machine embodying the present improvements. Fig. 2 is a sectional end view, upon a larger scale, of the work-supporting arm with the stitch-forming devices. Fig. 3 is a transverse section of the bearing bracket for the loop-taker shaft supporting frames. Fig. 4 is a plan, and Figs. 5 and 6 are elevations, taken from opposite sides, of the loop-taker and its 80 supporting bracket and the thread-case with its sustaining means, and Fig. 7 is a bottom plan view of the same. Fig. 8 is a plan and Fig. 9 is a perspective view of the thread-case with its supporting hanger, and Fig. 10 85 is a perspective view of the hanger and its support taken from the under side. Fig. 11 is a transverse section of the hanger and the thread-case with the contained bobbin. 90

As shown in the drawings, the frame of 95 the machine is constructed with the base 1 from which laterally extends the tubular work-supporting arm 2, and from which rises the hollow standard 3 with the overhanging tubular arm 4 terminating in the 100 head 5. The arm 4 has journaled therein the main-shaft 6 provided at its rearward end with the belt-pulley 7 and balance-wheel 8 and connected by usual or suitable means at its opposite end with the reciprocating needle-bar 9 carrying the needles 10. The main-shaft has secured thereon the bevel-wheel 11 meshing with a similar wheel 12

upon the vertical shaft 13 suitably journaled within the hollow standard 3 and connected at its lower end by means of the intermeshing bevel-gears 14 and 15 with the loop-taker actuating shaft 16 journaled within the work-supporting arm 2 and provided at its forward end with the bevel-gear 17.

Fixed within and at opposite sides of the arm 2 are the rigid parallel studs 18 entering the apertured bosses 19 of a spider-frame 20 having upon the upper end of its central web the cross-member 21 whose upper face affords a flat seat for the forward portion of the throat-plate. The frame 20 has intermediate and slightly below the bosses 19 the apertured central boss 22 concentric with the axis of the actuating shaft 16. Secured adjustably within the boss 22 by means of the set-screws 23 is the tubular pin 24 of one of the loop-taker shaft supporting brackets, and within such tubular pin is secured by means of the set-screws 25 the solid pin 26 of the other of the loop-taker shaft brackets, only one of which latter is represented in detail figures in the drawings, but both of which are of the same construction excepting in the character of the pins by which they are sustained upon the bracket 20.

The pin 26 has formed integral therewith at its rearward end a block 27 from which extends upwardly at right angles to said pin the loop-taker bearing stud 28. The block 27 is secured by means of the screw 29 to a boss 30 at the lower extremity of the laterally and upwardly extending bracket-arm 31 terminating at its upper end in the bearing block 32. Journaled upon the stud 28 is the rotary sleeve 33 having at its upper end the disk 34 and intermediate the ends the bevel-pinion 35 of one-half the diameter of and meshing with the bevel-wheel 17 of the actuating shaft 16. The sleeve 33 has between the disk 34 and pinion 35 a necked portion entered by the fork 36 at the free end of a pin 36 fitted within a transverse aperture of the bracket-arm 31 and adapted to restrain the sleeve against endwise displacement upon the stud 28.

Mounted upon the disk 34 is the loop-seizing member comprising the disk 37 and the upwardly and outwardly projecting segmental flange 38 extending through only a small portion of the circumference and provided in one end with the loop-taking beak 39 having upon its outer face the downwardly inclined rib or projection 40. The loop-taker flange is thus interrupted above the disk 37 throughout the greater part of its circumference.

Arranged in substantially axial relation with the loop-seizing member and embraced by the circular path of movement of this beak, is the thread-case which is formed with cylindrical body 41 open at the lower end

and closed at the upper end which is formed as a disk 42 with the diametrically arranged channel 43 having the marginal overhanging lips 44 extending laterally toward each other from the thickened portions 45 of the end disk. The lips 44 may be said to constitute suspension means by which the thread-case is hung from its support. The side wall of the thread-case has the usual thread-slit 46 extending from the open lower end with its extremity covered by the tension spring 47, and adjacent the loop-delivery end of the channel 43 there is provided a laterally projecting finger 48 having a thread-delivery aperture 49 through which the bobbin thread is led to the work from beneath the tension spring. Circumferentially intermediate and disposed below the tension spring and thread-delivery finger is the peripheral loop-detaining spur or shoulder 50 directed oppositely from the thread-slit 46.

The thread-case is sustained within the circular path of movement of the loop-taker beak 39 by means of the hanger 51 which is formed with the tongue 52 entering and loosely embraced by the channel 43 with its edges beneath the overhanging lips 44 and provided with the wedge-shaped loop-engaging extremity 53 extending beyond the periphery of the thread-case, said hanger being provided upon the side opposite the spur 50 and adjacent the base of the tongue 52 with a laterally and downwardly inclined stop-finger 54 and adjacent the same with the spring-arm 55 terminating in the downwardly inclined lip 56. The finger 54 and lip 56 afford stop-shoulders embracing the cast-off side of the thread-case adjacent the supporting tongue 52 and normally serve to lock the thread-case in position upon said tongue. By bending the arm 55 upwardly, the lip 56 may be withdrawn from operative relation with the thread-case and the removal of the latter over the end of the tongue 52 permitted.

The hanger 51 is shown provided with the suitably apertured foot 57 which is secured by means of screws 58 upon the depending flange 59 of the edgewise swinging supporting cover-plate 60 having upon its under face the stud 61 journaled in the bushing 62 of an aperture formed in the block 32 parallel with the loop-taker shaft 28. The bushing 62 is formed with the rectangular head 63 provided upon its upper face with the parallel locking ribs 64 one of which is adapted to enter a groove 65 in the lower face of the plate 60 and the other of which engages the edge of said plate at the opposite side of the stud 61.

The stud 61 is formed with an axial socket 61' in its lower end to receive a spring 66 interposed between the bottom of the same and the boss 22 and serving to nor-

5 mally press the cover-plate 60 upwardly for disengagement with the locking ribs 64. Fitted upon the threaded lower extremity of the stud 61 is the stop-collar 67 which is 10 secured thereon by means of the set-screws 68 and whose upper extremity affords an annular shoulder 67' for engagement with the nose 69 of an angular latch-lever 70 ful-crumed upon the cross-pin 71 within the slot 15 72 of the block 32 and provided with the wedge-shaped tail 73. The latch-lever 70 is normally maintained in locking relation with the stop-collar 67 by means of a spring 74 interposed between the bottom of the slot 20 72 and the inner extremity of a socket 75 formed in the adjacent edge of the latch-lever.

25 The block 32 is formed in one side with a slideway 32' in which is fitted the slide-plate 76 provided with an elongated aperture 77 to receive the shank of the screw 78 by which it is confined for endwise movement in the slideway. The slide-plate is provided at one end with the laterally offset cam projection 79 formed upon its outer face with the button 80 and having interposed between the bottom of a socket in its opposite face and the end of the block 32 the spring 81 for normally maintaining the cam projection 30 retracted from the tail 73 of the latch-lever 70.

35 The work-supporting arm 2 is provided at its extremity with the end cap 2' which is in practice formed with sockets to receive the extremities of the studs 18 to which it is secured. This cap is formed with the apertures 82 to receive and expose to the operator the ends of the buttons 80 by pressure upon one of which the respective latch-lever 40 70 may be tilted for disengagement from the stop-collar 67 whereby the cover-plate 60 is permitted to rise under the action of its spring 66 for disengagement from the locking ribs 63 so as to be turned for lateral retraction of the thread-case and exposure of the loop-seizing member beneath the same. The thread-case may obviously be returned to operative position by swinging the cover-plate upon its pivotal stud 61 to bring it 45 50 into register with the locking ribs 64 and then depressing the same for reengagement of the nose 69 of the latch-lever 70 with the stop-collar 67.

55 The throat-plate 83, which is provided with the usual needle-hole 83' and feed-dog apertures, is secured at its forward end upon the cross-member 21 of the spider-frame 20 and at its rearward end upon the raised portion 2" of the work-supporting arm 2, and 60 its opposite edges are shaped conformably with the adjacent edges of the laterally and downwardly inclined cover-plates 60 which abut the same. Intermediate the extremity of the body portion of the arm 2 and the end 65 cap 2' is secured the angular housing plate

84 which is in practice cut out in its upper edges to receive the flanges 59 of the cover-plates 60.

Mounted within the head 5 of the bracket-arm is the vibratory link take-up arm 85 70 constructed in substantial accordance with the United States patent to Philip Diehl No. 462,398, of November 3, 1891, which is adapted to coöperate with the needle and the loop-taker in drawing up the needle-thread 75 loops as they are carried to the farther side of the thread-case from the needle-hole by the loop-seizing member.

The thread-case is shown in Fig. 11 provided with a well-known form of axial bobbin-post 41' with expanded and split outer portion to confine thereon the hub of the bobbin 86.

In the operation of the machine, the needle descends, and as it begins to rise the 85 thread-loop thus presented is entered by the loop-taker beak and is spread thereby to substantially the full depth of the thread-case, the upper limb of the loop passing over the top of the latter and the lower limb being 90 temporarily detained upon the periphery of the thread-case by the spur 50 until it is deflected, in the continued travel of the loop-taker, beneath the lower edge of the thread-case. As the needle-thread loop is carried 95 around the first side of the thread-case toward cast-off position, its upper limb engages and is detained by the projecting extremity 53 of the tongue 52 adjacent the needle-aperture of the throat-plate, and in 100 its further movement the part adjacent the loop-taker beak encounters the edge of the tongue and the outer portion of the loop continues its travel beneath the thread-case hanger until the beak assumes a position in- 105 clined toward the center of the arm 2, when the take-up begins its loop-drawing action.

In this action, the tongue 52 serves as a loop-guiding element which is directed toward the needle-aperture, and in the continued movement of the take-up, the loop of needle-thread *a* (Fig. 8) is readily drawn between said tongue and the overhanging lips 44 resting upon the face of the same. The resistance offered by the thread-case to 110 this loop-drawing action is comparatively slight because the supporting connection between the thread-case and its sustaining tongue 52 comprises flat surfaces which distribute the weight throughout their lengths, 115 and the interposition of the thread-loop does not involve the bodily lifting of the thread-case, but the mere tilting of the same upon its supporting tongue. Another advantage of the present arrangement is in the position 120 of the thread-case supporting tongue which extends toward the needle-hole and therefore in the direction in which the thread-loop is drawn up by the take-up, so that 125 there is no cross-strain upon the thread-loop 130

such as there would be under a less favorable relation of the parts.

In machines for stitching tubular articles, such as that shown in the accompanying drawings, compactness is obviously a desideratum. This is attained in a considerable degree according to the present improvement by extending the actuating shaft 16 lengthwise of the tubular work-supporting

10 arm 2 for independent driving connection by suitable gears with the loop-takers mounted for rotation upon the divergently inclined radial studs 28, thereby permitting the upper face of the work-support to be inclined 15 downwardly from the central portion, as represented in Fig. 2, so as to reduce the area of cross-section which would be required with loop-takers rotating upon parallel axes.

As represented more particularly in Figs.

20 2 and 6, the loop-taker beak has a depth corresponding substantially with that of the thread-case, its downwardly inclined edge serving to force the inner limb of the loop below the bottom of the case, while the inclined rib or projection 40 serves to deflect the outer limb upwardly to the upper edge of the flange 38 and consequently to the upper face of the thread-case. In this loop-distending operation the spur 50 performs 25 no function, its office being merely to insure against the wrapping of the lower limb of the loop around the periphery of the case instead of rolling off the lower edge and beneath the same.

30 Having thus set forth the nature of the invention, what I claim herein is:—

1. In a sewing machine, the combination with a loop-seizing element of a thread-case member and a hanger member therefor, one 40 of said members being formed with a channel having overhanging lips and the other of said members having a portion entering and loosely embraced by said channel and engaging said overhanging lips, one of said 45 members being normally stationary while the machine is in operation.

2. In a sewing machine, the combination with a loop-seizing member, of a normally stationary thread-case provided in its upper 50 side with a channel having overhanging lips, and a hanger having a member entering and loosely embraced by said channel and engaging said overhanging lips.

3. In a sewing machine, the combination 55 with a throat-plate having a needle-aperture, and a needle reciprocating through said aperture, of a thread-case provided in its upper side with a channel having overhanging lips, and a hanger having a member directed substantially toward the needle-aperture of said throat-plate and entering and loosely embraced by said channel and engaging said overhanging lips.

4. In a sewing machine, the combination

with a loop-seizing member, of a substantially cylindrical thread-case provided in its upper side with a channel having overhanging lips, and a hanger having a member arranged crosswise of the axis of and projecting laterally beyond the body of said thread-case and entering and loosely embraced by said channel and engaging the overhanging lips thereof.

5. In a sewing machine, the combination with a loop-seizing member, of a thread-case 75 provided in its upper side with a channel having overhanging lips, and a thread-case hanger comprising a tongue entering and loosely embraced by said channel and engaging said overhanging lips and provided with 80 means for engaging the thread-case exterior to said channel for restraining it against displacement upon said tongue.

6. In a sewing machine, the combination with a loop-seizing member, of a thread-case 85 provided in its upper side with a channel having overhanging lips, and a thread-case hanger comprising a tongue entering and loosely embraced by said channel and engaging said overhanging lips and provided with 90 thread-case confining shoulders at one side of said tongue and embracing between them one side of the periphery of the thread-case exterior to said tongue.

7. In a sewing machine, the combination 95 with a loop-seizing member, of a thread-case provided in its upper side with a channel having overhanging lips, and a thread-case hanger comprising a tongue entering and loosely embraced by said channel and engaging said overhanging lips and provided at 100 one side of said tongue with thread-case confining shoulders, one of which is retractable from the thread-case and embracing between them one side of the periphery of the thread-case.

8. In a sewing machine, the combination with a loop-seizing member, of a thread-case provided in its upper side with a channel having overhanging lips, and a thread-case hanger comprising a tongue entering and loosely embraced by said channel and engaging said overhanging lips and provided at one side of said tongue with thread-case 115 confining shoulders, one of which is carried by a spring-arm yielding transversely of said tongue and embracing between them one side of the periphery of the thread-case.

9. In a sewing machine, in combination, 120 a thread-case provided in its upper side with a channel having overhanging lips and upon its periphery at one side of said channel with a loop-detaining shoulder, a hanger having a member entering and loosely embraced by said channel and engaging said overhanging lips, and a loop-seizing member constructed with a loop-distending beak 125

having a depth substantially equivalent to that of the thread-case.

10. In a sewing machine, in combination, a thread-case provided in its upper side with 5 a channel having overhanging lips and upon its periphery at one side of said channel with a loop-detaining shoulder, a loop-seizing member comprising a segmental portion having a length less than a semi-circumference and provided with a beak, a hanger having a member entering and loosely embraced by said channel and engaging said overhanging lips, and a support for said hanger movable transversely of the axis of 10 said loop-taker for retraction of the thread-case laterally therefrom.

11. In a sewing machine, in combination, a thread-case, a loop-seizing member provided with a beak and laterally open 20 throughout a space exceeding the width of the thread-case, a hanger by which the thread-case is suspended within the path of movement of said beak, a support for said hanger pivotally mounted substantially 25 parallel with the axis of movement of said beak, and means for locking said support in operative position.

12. In a sewing machine, in combination, a thread-case, a loop-seizing member provided with a beak and laterally open 30 throughout a space exceeding the width of the thread-case, a hanger by which the thread-case is suspended within the path of movement of said beak, a support for said hanger, a fulcrum concentrically and endwise of which said support is movable, and means for locking said support in operative position.

13. In a sewing machine, in combination, 40 a thread-case, a loop-seizing member provided with a beak and laterally open throughout a space exceeding the width of the thread-case, a hanger by which the thread-case is suspended within the path of movement of said beak, a support for said hanger, a fulcrum concentrically with and endwise of which said support is movable, fixed locking means for normally restraining 45 said support against its concentric movements, and a latch device for maintaining the support against movement endwise of said fulcrum whereby it may be disengaged from said locking means.

14. In a sewing machine, in combination, 50 a thread-case, a loop-seizing member provided with a beak and laterally open throughout a space exceeding the width of the thread-case, a hanger by which the thread-case is suspended within the path of movement of said beak, a support for said hanger, an endwise movable fulcrum-pin rigidly attached to said support, rigidly sustained locking means for said support, a 55 spring for disengaging the support from its

locking means, and a latch device acting in 60 opposition to said spring for maintaining the support in operative relation with its locking means.

15. In a sewing machine, in combination, 65 an actuating shaft, a frame mounted concentrically with said shaft, a loop-taker shaft journaled in said frame in transverse relation with said actuating shaft, a rotary loop-seizing member provided with a beak and fixed upon said loop-taker shaft, intermeshing gears fixed upon said actuating shaft and loop-taker shaft, respectively, a thread-case suspended within the path of movement of said beak, and means for adjusting the position of said frame concentrically with said actuating shaft. 70 75 80

16. In a sewing machine, in combination, 85 a reciprocating needle, a rotary loop-seizing hook movable upon an axis inclined to said needle, a thread-case, and a hanger by which the thread-case is suspended in a normally stationary position within the field of action of said hook and movable laterally of the axis of rotation of said hook for retraction of the thread-case from normal operative 90 relation therewith.

17. In a sewing machine, in combination, 95 two reciprocating needles, rotary loop-seizing hooks movable upon axes inclined to each other and to said needles, thread-cases for the respective hooks, and hangers by which said thread-cases are suspended normally within the fields of action of their respective hooks and independently movable laterally of the axes of their respective hooks for retraction of said thread-cases from operative 100 relation therewith.

18. In a sewing machine, in combination, 105 a reciprocating needle, a rotary hook coöperating therewith, a thread-case for said hook, and a hanger by which the thread-case is suspended in a normally stationary position within the field of action of the hook and movable laterally of the axis of rotation of the latter for retraction of the thread-case 110 from normal operative relation with the hook.

19. In a sewing machine, in combination, 115 two needles reciprocating in unison, loop-seizing hooks coöperating therewith and mounted for rotation upon axes inclined to the respective needles and to each other and embraced by a common plane, an actuating shaft, independent operative connections consisting of intermeshing gears between said shaft and said hooks, and thread-cases sustained within the fields of action of said hooks.

20. In a sewing machine, the combination 120 with the frame comprising a standard and a hollow work-supporting arm extending laterally therefrom, of two reciprocating needles, loop-seizing hooks coöperating

- therewith and mounted for rotation upon axes inclined to the respective needles and to each other, an actuating shaft extending longitudinally of the work-supporting arm, 5 independent operative connections between the actuating shaft and said hooks, and thread-cases sustained independently of each other and within the range of action of the respective hooks.
21. In a sewing machine, the combination with the frame comprising a standard and a hollow work-supporting arm extending laterally therefrom, of two reciprocating needles, loop-seizing hooks co-operating therewith and mounted for rotation upon axes inclined to the respective needles and to each other and embraced by a plane transverse to the work-supporting arm, an actuating shaft extending longitudinally of 15 the work-supporting arm, independent operative connections between the actuating shaft and said hooks, and thread-cases sustained independently of each other and within the range of action of the respective hooks.
22. In a sewing machine, the combination with the frame comprising a standard and a hollow work-supporting arm extending laterally therefrom and formed with a wall 30 having a laterally removable section, of a reciprocating needle, a loop-seizing hook co-operating therewith, a thread-case, and a hanger by which the thread-case is suspended normally within the field of action of said hook and mounted upon said removable section of the work-supporting arm whereby the thread-case is retracted from operative relation with the hook in the removal of said section.
23. In a sewing machine, the combination with a loop-seizing member, of a thread-case provided with suspension means below which the thread-case depends, and normally stationary supporting means loosely 40 engaging said suspension means, and thus affording clearance space for passage of the needle-loops.
24. In a sewing machine, the combination with a loop-seizing member, of a cylindrical thread-case provided at its upper end- 50
- face with an undercut recess, and normally stationary supporting means loosely entering said recess and suspending said thread-case within the field of action of said member, while permitting passage of the needle 55 thread loops about said thread-case.
25. In a sewing machine, a rotary loop-seizing member, a cylindrical thread-case, and means independent of said member for suspending said thread-case within the field 60 of action thereof, and in substantially coaxial relation therewith.
26. In a sewing machine, the combination with a loop-seizing member, of a thread-case provided in its upper side with a channel having overhanging lips, and a hanger having a member entering and loosely embraced by said channel and engaging said overhanging lips, there being sufficient space 65 between said hanger and the walls of said channel to permit passage of the needle 70 loops therethrough.
27. In a sewing machine, the combination with a reciprocating needle, a loop-seizing element and a take-up, of a thread-case 75 member and a hanger member therefor, one of said members being formed with a channel having overhanging lips and the other of said members having a portion entering and loosely embraced by said channel and engaging said overhanging lips, there being sufficient space provided between said members to permit passage of the needle-loops 80 therebetween as they are drawn up by the take-up.
28. In a sewing machine, the combination with a loop-seizing member, of a thread-case provided in its upper side with a channel having overhanging lips, and a hanger having the form of a flat tongue and entering and loosely embraced by said channel and engaging said overhanging lips.
- In testimony whereof, I have signed my name to this specification, in the presence of two subscribing witnesses.

ALBERT H. DEVOE.
